UNITED STATES PATENT OFFICE.

JOHN DEAN, OF RACINE, WISCONSIN.

HAND HAIR-CLIPPER PART.

Application filed May 17, 1926. Serial No. 109,756.

This invention relates to fixed handle and cap units for hand hair clippers particularly of the so-called torsion spring type; and the objects and nature of the invention will be readily understood by those skilled in the art in the light of the following explanations of the accompanying drawings that show what I now believe to be the preferred mechanical expression or embodiment of my invention from among other forms, arrangements and constructions within the spirit and scope thereof.

Hand hair clippers of the type mentioned, as now found on the market, embody a flat bottom blade or comb plate that constitutes the base plate of the implement; a cooperating reciprocating blade that slides on the top face of the base plate; a cap and the fixed handle formed by a single casting; the lever handle composed of a single casting and fulcrumed on a hollow pindle formed by a bushing rigid with the cap, and receiving the main bolt passing through the base plate, pindle and cap and having the clamping nut located above the cap, and a torsion spring arranged within the cap surrounding the hub of the lever handle with one end bearing on the lever handle and the other end confined to the cap, the lever handle having a forwardly extending nose within the cap loosely entering the reciprocating blade for the purpose of reciprocating said blade as the lever handle is oscillated. These clippers now on the market are unduly expensive in production, mainly because of the one piece casting forming the cap and fixed handle which as a foundry or casting problem is very difficult and expensive to produce, and which when properly produced requires much expensive hand work in preparation and fitting for assembly, and in the proper preparation and finishing thereof to receive the necessary plating and in the production of the approximately-perfect finished plated article without objectionable blemishes. In fact, about one half of the factory or manufacturing cost of these old clippers, is chargeable against the finishing operations required mainly due to the comparatively heavy complicated casting that forms the cap and fixed handle, and the variations in such castings which may run as high as from thirty to forty one thousandths of an inch or more even in otherwise perfect castings.

An object of the invention is to produce

an improved fixed handle and cap unit for hand hair clippers with the end in view of reducing hair clipper production costs.

With this and other objects in view, the invention consists in certain novel features in structure or in formation or in combinations or arrangements as more fully described and specified hereinafter.

The invention also involves an externally plated fixed handle and cap unit for hair clippers wherein the cap is produced by a method, other than by casting, which will necessarily produce caps of a series uniform and accurate in essential dimensions and of exterior surface conditions ready for the plating operation without requiring preliminary expensive hand finishing; and wherein the fixed handle portion consists of a simple malleable casting the exterior surface of which has been brought to condition for the plating process by any suitable mechanical finishing operation without expensive hand labor, with these two members so relatively formed as to fit one within the other for rigid union by a joint preferably concealed within the cap, providing anchorage for the trunnion located within the cap, which trunnion is preferably utilized for riveting or fixing the handle portion and cap together.

Referring to the accompanying drawings that form a part hereof:—

Fig. 1 is a side elevation of the unit, the handle portion being partially broken away.

Fig. 2 is a top plan.

Fig. 3 is a vertical section.

Fig. 4 is a bottom plan.

Fig. 5 is a detail detached perspective of the cap element.

Fig. 6 is a detail detached perspective of the handle element.

Fig. 7 is a front view of the cap element partially broken away.

Fig. 8 is a plan view of a blank from which the cap unit can be pressed up by dies.

The cap 4, is hollow and in the form of an inverted cup or hood, and is formed by dies and preferably composed of sheet or plate steel.

This cap is provided with a vertical longitudinally hollow trunnion 5, rigid with and depending within the cap from the flat top wall thereof, and the bore of this trunnion is open at the top of the cap, for the passage of the clamping bolt of the hair clipper

assembly, hereinbefore described. The fixed handle 8 is rigid with the cap and projects upwardly and rearwardly from an upper rear corner of the cap. The cap is open at 5 the opposite rear corner for the passage and free swing of the upwardly and rearwardly extending lever operating handle of the said hair clipper assembly, wherein said operating lever is formed with a vertical hub 10 mounted to oscillate on the trunnion 5.

The cap 4 is formed to approximately cover and enclose the hair clipper reciprocating blade up to the toothed front portion thereof. The lower front edge portions of 15 the cap are formed to bear on and hold the blade down to operative sliding engagement with the top face of the hair clipper base plate with the teeth of the blade in operative sliding engagement with the teeth of the 20 base plate, and to hold the blade to straight line reciprocation.

The operating lever handle and its hub and nose, are usually formed by a single casting, which is small and of such form that 25 it can be economically produced, and then economically finished for electro-plating by mechanical processes or means (such as by the mechanical tumbling process) without requiring expensive hand work. The same 30 is true of the handle 8, apart from the cap. I hence, form the handle 8, separately from the cap, and provide the same with a flat laterally enlarged securing head 8^a, integral with the handle and projecting forwardly 35 from the lower or front end thereof. This handle portion 8 with its securing head is small and of such shape that it can be economically produced in one piece by casting and economically finished for electroplating 40 by mechanical processes or means without requiring expensive hand labor.

The public and trade requirements necessitate electroplating the exterior surfaces of the cap, as well as the handles, and hence the 45 cap surfaces must be in condition to receive electroplating and produce a proper plated surface. Also, caps must be produced accurately and uniformly dimensioned, to avoid expensive hand fitting and machining 50 work, preparatory to assembling with the blades, etc. It is not possible to attain these ends, by either casting the caps separately or in one piece with the handles 8. I attain the results desired by forming the caps separately, not by a casting operation, but by the 55 use of plate metal, such as sheet or plate steel, and dies by which the plate or sheet metal is accurately and uniformly shaped to the exact form and dimensions required 60 with exterior surfaces that can be electroplated to produce the plated surfaces required without expensive finishing preparatory to plating. The dies will produce a series of plate metal caps that are accurately 65 uniform in shape and dimensions to meet

the predetermined requirements, for quick and accurate assembly with other parts of the clippers.

The separately produced caps and handles 8 are rigidly and permanently united in 70 proper relation before electro-plating, with the formation of a joint at the union between handle and cap that is approximately hidden or concealed, after the cap handle unit is plated, and that does not result in 75 an objectionable blemish in the plated surfaces at the union.

In the particular example shown, the cap is composed of cold rolled sheet or plate 80 steel shaped up by the use of dies, although I do not wish to limit all features of my invention to a cap composed of cold rolled steel.

This sheet or plate metal cap is formed 85 or shaped to fit and interlock with the cast handle member 8, in such manner as to permit the formation of the desired rigid permanent union between the handle and cap members. For instance, in the example 90 illustrated, the sheet metal cap is formed with a flat top wall 13, at its outer rear corner having a cut off portion or notch forming a vertical opening 12, while the upper portion of the rear depending wall 14 of the cap is formed with a laterally elongated 95 horizontal slot 15, at one end portion merging into vertical opening 12, and at the opposite end opening into the open rear corner portion of the cap, said slot being approximately flush with the bottom surface 100 of the flat top wall 13 of the cap.

The cap, with its said rear upper openings, is so formed with respect to the head 8^a and its junction with the handle portion 8, that said parts can be assembled (after 105 the handle portion 8 has been finished for plating as by a mechanical tumbling treatment) by slipping the head 8^a, forwardly into the cap through slot 15 until the handle 8 where it rises from the head 8^a fits 110 and closes the vertical opening 12 and the rear edge of the head 8^a, closes the slot 15 and is flush with the rear vertical face of the rear wall 14, and the front edge of the head 8^a approximately abuts the upper part 115 of the inner surface of the depending front wall of the cap. When the handle and cap are thus assembled, the head 8^a is concealed within the cap parallel with the cap top wall 13 and fitting the bottom surface 120 thereof and approximately fully occupying the upper end or top portion of the interior of the cap. While the cap and handle are thus held assembled in the relative positions that they are to assume permanently 125 in the completed handle-cap unit, the cap and handle head are permanently and rigidly united by any suitable means or method, as by brazing, soldering, riveting, welding, or otherwise. The head 8^a, within the cap 130

thus faces the underside of cap top wall 13 and is united thereto and the cap top is thus laminated or of double thickness. This double-thickness cap wall can then be 5 vertically bored or drilled to form the bore that receives the upper end of the hollow trunnion 5, and in which the same is rigidly anchored to the cap. The handle portion head 8^a and the sheet steel top wall 10 of the cap provide a thick deep foundation for the strong rigid anchoring of the trunnion.

I prefer, however, to utilize the metal bushing or tube that forms the trunnion 5, 15 as the rivet or means for permanently and rigidly fixing together the handle and cap elements. The handle end 8^a, is shaped to conform to the interior top portion of the cap and to accurately fit therein and 20 engage the base portions of the depending cap wall. The handle end 8^a, is held rigidly in its normal position within the cap and the hole for the trunnion is drilled through the end 8^a and the cap top, or the holes 25 in said parts can be separately formed, and the parts then held together with the holes in registration, while the trunnion is fitted in said holes and upset or expanded to rigidly rivet and lock the parts permanent- 30 ly together.

After the handle portion and cap have thus been permanently united by the joint or union concealed within the cap, exterior surfaces of the handle-cap unit thus formed, 35 can be finished for the market by electro-plating and burnishing.

The unit thus formed can be easily assembled with the blades, operating handle, 40 spring and bolt, without expensive hand work and fitting to provide the necessary clearance within the cap for working parts. The sheet steel shaped by the dies will accurately produce the cap according to the 45 predetermined dimensions necessary to provide clearance and accurate fitting of the cap with and to the blades.

The caps can be pressed up by dies from the flat plate or sheet steel blank of Fig. 8, composed, say, of one sixteenth cold rolled 50 mild steel, and the top hole and back slot can be punched after the cap has been formed by the dies, although I do not wish to so limit all features of my invention, as other forms, material, and steps might be 55 employed and followed.

The handle section 8, is preferably composed of a malleable iron casting with its head or applying end 8^a accurately sized 60 by dies to snugly and closely fit within the cap top and to produce uniform thickness.

It is evident that various changes, modifications and variations might be resorted to without departing from the spirit and scope of my invention, and hence I do not wish to 65 limit myself to the exact disclosures hereof.

What I claim is:

1. An exteriorly plated fixed handle and cap unit for hand hair clippers, comprising a separately formed cap, and a separately 70 formed handle extending into the cap and exteriorly from the cap and fixed thereto within the cap, whereby the union between the handle and cap is covered by the cap.

2. A fixed handle and cap unit for hand 75 hair clippers, comprising a separately formed cap having an opening at its rear portion, a separately formed handle extending from the interior of the cap to the exterior thereof through and approximately 80 closing said opening, said handle formed with an end fitted within the cap and against and fixed to the cap top, and a fixed trunnion anchored in said end and the cap 85 top.

3. An exteriorly plated fixed handle and cap unit for hair clippers, comprising a cast metal handle of a shape to permit surface finishing by mechanical tumbling operation, a sheet steel pressed up cap shaped to 90 interiorly receive an end of said handle with the handle extending from the interior to the exterior of the cap, said handle end being fitted within and therein fixed to the cap and covered thereby with the handle and 95 cap in permanent operative handle and cap unit form.

4. A fixed handle and cap unit for hair 100 clippers, comprising a pressed up sheet steel cap, a cast metal handle of shape for surface finishing by mechanical tumbling operation and having an end fitting said cap, and a fixed trunnion securing together the handle and cap in permanent operative handle and 105 cap unit form.

5. A fixed handle and cap unit for hair 110 clippers, comprising a pressed up sheet metal cap, a malleable casting handle having an end formed to snugly fit the upper part of the interior of the cap, and a trunnion within the cap and anchored within the cap 115 top and handle end and rigidly fixing said parts together.

6. A fixed handle and cap unit for hair 120 clippers, comprising a cap element, a handle element having an end head fitted to the cap, and a trunnion passing through said head and the adjacent cap wall and riveting said parts rigidly together.

Signed at Racine, Wisconsin, this 11th day of May 1926.

JOHN DEAN.
